UNITED STATES PATENT OFFICE.

NEWTON RUSK, OF SAN DIEGO, CALIFORNIA, ASSIGNOR OF ONE-HALF TO DAVID GOCHENAUER, OF SAN DIEGO, CALIFORNIA.

AUTOMATIC SASH-LOCK.

1,080,172.

Specification of Letters Patent.

Patented Dec. 2, 1913.

Application filed July 8, 1913. Serial No. 777,310.

To all whom it may concern:

Be it known that I, NEWTON RUSK, a citizen of the United States, residing at San Diego, in the county of San Diego and State 5 of California, have invented certain new and useful Improvements in Automatic Sash-Locks, of which the following is a specification.

The object of this invention is to provide 10 a lock to be placed on the meeting rails of vertically sliding window sashes which will automatically draw the two sashes together and lock them by the operation of lowering the previously raised lower sash, or the reverse if the upper sash was lowered.

A further object is to provide a sash fastening device which can only be unlocked to release the two window sashes by a lateral pressure upon the locking levers, and the 20 further object is to so construct and locate said locking levers that the lock can not be picked from the outside of the house.

Another object of my invention is to provide a window lock having a small number 25 of parts, all of which are inexpensive to manufacture, and which are readily assembled, thereby insuring low cost of manufacture and to provide a lock which will be durable and easy to operate.

30 I accomplish the above and other objects which will be hereinafter fully described and pointed out, by the mechanism illustrated in the accompanying drawing, in which—

35 Figure 1 is a view in side elevation looking at the inside of the window, of a portion of the meeting rails of the sashes of a window equipped with my invention which is shown in locked position. Fig. 2 is a vertical section of the window on the line 2—2 of Fig. 1 looking toward the sash lock. Fig. 3 is a vertical section on the line 3—3 of Fig. 2. Fig. 4 is a top plan view of the catch member of the lock detached from all 40 other parts. Fig. 5 is an elevation of same looking in the direction of the arrow 5 shown in Fig. 4 and Fig. 6 is a top plan view of the spring of the lock removed from the box or casing in which it is housed in the 45 assembled lock.

Like characters of reference indicate like parts throughout the several views of the drawing.

7 is the meeting rail of the upper sash and 8 the meeting rail of the lower sash.

55 9 is the body of the lock having horizontal ears 10 with holes for the passage of screws, as shown, by means of which the body 9 is secured to the meeting rail 7 of the upper sash. The interior of the body 9 is hollow to form a box or casing into which the lower end of a latch 11 is extended through a longitudinal slot 12. At the other end of the body 9 from the slot 12 is a standard 13, preferably formed as an integral portion of 60 the body 9 and having a transverse slot 14 near its base. This standard has the tapering side 15, as shown in Fig. 2.

The lower end of the latch bar 11, which is inserted through the slot 12 into the hollow body 9, is bent at right angles as shown in Fig. 3 and this bent end is pivoted to the body 9 by means of a transverse pin 16. Mounted within the hollow body 9 is a leaf spring 17, one end of which has a bearing 75 upon a transverse pin 18 supported by the body 9, and the other end 19, which is preferably reduced in width as shown in Fig. 6, is passed out of the hollow body or box 9 through a suitable slot in the top of the box 80 at the base of the standard 13, as shown in Fig. 3, and is bent toward the latch bar 11, as shown, and terminates against the under side of a locking lever 20. This locking lever 20 passes through a suitable slot 85 formed in the latch bar 11 and is pivotally secured to the latch bar by a pin 21. The latch bar 20 extends through the slot 14 in the standard 13 and terminates with an upwardly bent hook 22 which is normally 90 locked in contact with the outer side of standard 13 by the pressure against the under side of the latch bar 20 of the end 19 of spring 17. The vertical dimensions of the slot 14 are sufficient to allow the hook 22 95 to be moved down by a lowering movement of the latch bar 20 out of engagement with the standard 13, thereby releasing the latch bar 11 so as to permit the latter to be swung in a direction away from the standard 13, which movement is permitted by the suitable extension of the slot 12. The inner end of the slot 12 forms a stop to limit the movement of the latch bar 11 in the direction of the standard 13. The lower end of the latch 100 bar 11 is in contact with the spring 17, and

in order to secure this contact as far away as possible from the pin 17 I provide a downward lug or heel extension 23 on the end of the latch bar. Thus the tension of the spring 17 has a tendency to hold the latch bar in a normal substantially vertical position in contact with the inner end of the slot 12. The upper end of the latch bar 11 is extended in the direction of the standard 13 to form a head, the base of which forms a locking shoulder. This head is beveled on its side toward the standard 13 to cause it to be moved automatically away from the standard when the catch on the other sash is lowered into contact with it.

The catch 24, just referred to, is secured by screws or other suitable means to the meeting rail 8 of the lower sash. The vertical member of this catch has a horizontal extension which is projected toward the latch bar 11 and extends under the shoulder of the head on said bar when in locked position. This horizontal member 25 is provided with a slot 26 for the passage of the standard 13 through the horizontal member. The dimensions of the slot 26 are such as to fit the standard 13 closely when the two meeting rails 7 and 8 of the window sashes are in locking position on a level with each other. The tapering shape of the standard 13 enables the pointed end to enter the slot readily and then, by the contact of the sloping edge 15 against the catch at the end of the slot 26 the rails are brought together to the position shown in Fig. 2.

In order to automatically release the hook 22 of the horizontal latch bar 20 and thereby unlock the latch bar 11 the horizontal member 25 of the catch 24 has a part of the member on one side of the slot 26 bent down in U-shape to form an extension 27 which contacts with the hook 22 and disengages the latch bar 20 before the horizontal member 25 on the other side of the slot 26 has come in contact with the beveled surface of the head on the latch bar 11. The latch bar 11 is thus released automatically.

When the window is locked by means of my invention it is necessary, in unlocking the sashes, to first swing the hook 22 on lever 20 down to release the latch bar 11, and then swing the two bars to the right, together. This is done manually and for this purpose the lever 20 is provided with the finger-plate extension 30 on its end opposite the hook 22. To operate the device the thumb is placed against the beveled side of the head of the latch bar 11 and the finger against the plate 30; then a pressure of the two together will first unlock the lever 20, and that will release the latch bar 11 and the two can be swung to the right by a continuation of the same movement. When the two sashes are locked the hooked end 22 projects through slot 14 above the

bent portion of member 25 thereby insuring a locked condition of the parts. The interior space of the U-shaped portion affords clearance for the hooked end of the bar 20 when that end is lowered.

While I have described my invention with more or less minuteness as regards details of construction and arrangement and as being embodied in certain precise forms I do not desire to be limited thereto unduly or any more than is pointed out in the claims. On the contrary, I contemplate all proper changes in form, construction and arrangement, the omission of immaterial elements and the substitution of equivalents as circumstances may suggest or necessity render expedient.

I claim:

1. In a window lock, a body member attached to one sash, a standard extending vertically from said body and having a transverse slot, a catch plate attached to the other sash having a slot through which the standard passes when the window is locked, a latch bar pivoted to the body and adapted to swing into locking engagement with the catch plate, and a locking bar pivoted to the latch bar and passing above the catch plate and through the slot in the standard.

2. In a window lock, a body member attached to one sash, a standard having a vertical taper extending upwardly from said body and having a transverse slot, a catch plate attached to the other sash and having a slot through which the standard passes when the window is locked, a latch bar pivoted to the body and adapted to swing to and from the catch plate and having a head with an abrupt shoulder to lock upon the catch plate said head having an oblique face on the side next to the catch plate, and a spring to press the latch bar normally toward the standard and a locking bar pivoted to the latch bar and passing above the catch plate and through the slot in the standard.

3. In a window lock, a body member attached to one sash, a vertically tapering standard extending upwardly from said body said standard having a transverse slot, a catch plate attached to the other sash having a slot through which the standard passes when the window is locked, a latch bar pivoted to the body and adapted to swing into locking engagement with the catch plate and a locking bar pivoted to the latch bar and passing through the slot in the standard and terminating with a hook to engage the opposite side of the standard from the latch bar.

4. In a window lock, a hollow body member attached to one sash, an upwardly extending tapering standard on said body, said standard having a transverse slot, a catch plate attached to the other sash and having a slot through which the standard passes when the window is locked, a latch bar pivoted with-

in the hollow body, said bar having a head with an abrupt shoulder to rest upon and lock the catch plate said head having an oblique side next to the catch plate and said 5 latch bar having a transverse slot, a lock bar passing through the slot in the latch bar and pivoted in said slot said lock bar also passing through the slot in the standard and terminating with an upward hook at that 10 end and with a finger plate at its other end, and a spring within the hollow body to nor-

mally press the latch bar into locking position with the catch plate said spring extending into contact with the lock bar.

In witness whereof, I have hereunto set 15 my hand and seal at San Diego, California, this 18 day of June A. D. one thousand nine hundred and thirteen.

NEWTON RUSK. [L.S.]
